UNITED STATES PATENT OFFICE.

JAROSLAW K. KOSTKO, OF FERGUSON, MISSOURI.

BRUSH HOLDER FOR REVOLVING BRUSHES.

Application filed May 13, 1927. Serial No. 191,100.

This invention relates to improvements in stationary commutators and revolving brush holders carrying brushes adapted to cooperate with stationary or with moving commutators.

The objects and features of this invention will appear from the description and drawings and will be more particularly pointed out in the claims.

10 In the accompanying diagrammatic drawings Figs. 1 and 2 show two views of one embodiment of my invention, Figs. 3, 4 and 6, 7 show two views of two other embodiments, Fig. 5 shows one view of a fourth embodiment and Figs. 8, 9 and 10 are explanatory diagrams.

Referring more particularly to Figs. 1 and 2, mounted on the revolving shaft 2 of a motor or generator is a spider 3 which carries any suitable number of brackets 9 insulatingly held to the spider 3 by means of the bolts 8. Each bracket 9 supports a pin 12 on which are pivotally mounted two pairs of scissor-like arms 10, 11 and 10', 11', one 25 pair being controlled by the coil spring 7, the other by the coil spring 7' and each spring tending to close one pair of scissor-like arms.

The stationary member of the dynamo-electric machine is provided with a number 30 of brackets 20 which support the stationary commutator 6. This commutator is circular and of T-shaped cross-section. The stem of the T is directed inwardly towards the shaft 35 of the motor and the two sides of this stem, which are in planes perpendicular to the shaft, form the working surfaces or faces of the stationary commutator which may have any desired number of segments. These segments are radially insulated one from the other and held together by a metal ring 35 insulated from the commutator segments by strips of insulation 21 and preferably shrunk over the properly assembled T-shaped segments of 6. The ring 35 is carried by the brackets 20 and held in place by the ring 18 and the studs 19. This commutator is connected to a winding which is not shown but which is located on the stator or stationary 50 member of the dynamo-electric machine.

Oppositely located brushes 4, 5, which may be of carbon or any other suitable material, cooperate in pairs with the two radial working faces of the T-shaped commutator and are 55 yieldingly held in operative relation to said faces by the two pairs of scissor-like arms

10, 11 and 10', 11', loosely pivoted on 12, as shown in Fig. 1, and controlled by the springs 7 and 7'. Each brush carries on its outer end a metal cap 14, 15 and a pin 16, 17 passes 60 through each brush and its cap. Each pin runs approximately parallel to the working face of the commutator, projects on each side of its brush and its axis is about parallel to a tangent to the outer circumference of the 65 commutator. The arms 10 and 10' engage with the pin 16 of the brush 4 located on one side of the commutator segments, while the arms 11, 11' similarly engage with the pin 17 of the oppositely located brush 5. The pins 16 and 17 loosely fit into suitably shaped notches provided in each of the arms as more clearly shown in Fig. 10.

When the shaft 2 revolves it carries with it the brackets 9, the spring-controlled arms 10, 11, 10', 11' and the brushes 4, 5 with which they cooperate. The commutator 6 is stationary. The brushes 4, 5 may be connected to a winding or windings on the revolving member of the machine.

It is seen that relative movement between brushes and the revolving member is in no way hindered in an axial direction. Thus, if the commutator is stationary and the shaft moves axially to and fro due, for instance, to end play the brushes remain in cooperative relation to the commutator, in other words the whole brush surface normally in contact with a working face of the commutator remains in contact with said face while the revolving member moves to and fro relatively to the brush and in a direction at right angles to the working face of the commutator. During such axial movement of the revolving member the hubs of the arms 10, 11, 10', 11' move on the pin 12 and the notches in said arms move on the pins 16 and 17. When the revolving member moves axially the axial displacement between original points of contact between the pins forming part of said brushes and the notches in the arms 10, 11, 10', 11', and between pin 12 and the hubs of said arms, is very considerably less than the concurrent axial displacement of the revolving member. In Figs. 1 and 2 the centrifugal force acting on the brushes 4 and 5 increases the pressure on the pins 12, 16, 17 but does not materially affect the pressure of the brushes on the working faces of the commutator.

A brush is readily removed for examination or replacement by pulling the corresponding arm away from the commutator

to a sufficient extent and slipping the brush pin out of the notches in said arms.

It will be readily understood that the working faces of the commutator need not be exactly at right angles to the axis of the machine or of that of the revolving member, the stem of the T may, for instance, have somewhat converging instead of parallel sides. Furthermore, it is not necessary to operate the brushes in groups of two. One of the brushes 4 or 5 in Fig. 1 can, of course, be omitted.

In the embodiment shown in Figs. 3 and 4 a U-shaped member 31 is secured to the bracket 9 by means of the rivet 34 and prevented from turning about said rivet by means of the pin 22. This U-shaped member forms a box-like brush holder adapted to guide the brush 5, provided with the metal cap 15, into operative relation with the radial working face of the commutator 6. This commutator has but one working face and is of L-shaped cross section. The brush is yieldingly pressed into surface contact with the commutator face by means of the lever 25 loosely mounted on the pin 22 and under the control of the coil spring 26, one end of which passes through and is held in the hole 32 provided in one of the sides of the U-shaped member 31 while the other end of this spring presses against the lever 25. Shoulders provided in the sides of the member 31 limit the travel of the brush in the direction of the shaft and the cross member of the U-shaped piece limits the travel of the brush in the opposite direction. The brush 5 is also under the control of the spring 30, one end of which is attached to a hook held in the cap 15 while the other is attached to the hook 37 mounted on a pin passing through the side members of 31. The spring 30 opposes the action of the centrifugal force on the brush 5 and is preferably so dimensioned that in normal operation the brush 5 floats between the stops limiting its radial movement.

In the arrangement shown in Figs. 3 and 4 the revolving brush 5 is free to remain in cooperative relation to the commutator face, in other words to retain a surface contact with said face, while the revolving member moves axially to and fro carrying the bracket 9 with it. This brush is held in yielding contact with the commutator face by the lever 25 and spring 26 and the effect of the centrifugal force on brush 5 is sufficiently counteracted by the spring 30 to prevent said brush from being forced into intimate contact with the cross piece of the member 31. A considerable movement of the brush in an axial direction or of the revolving member along a line normal to the commutator face corresponds to only a slight codirectional displacement between original points of contact between parts of the mechanism which yieldingly hold the brush in contact with the working

face of the commutator and which counteract the action of the centrifugal force on the brush. Thus, a considerable axial displacement of the revolving member causes but a slight movement between the hub of the lever 25 and the pin 22, a slight movement between the point of the lever 25 and the cap 15 of the brush and a slight movement between the ends of the spring 30 and the hooks with which said ends cooperate. By forcing the lever 25 back away from the brush 5 it is possible to withdraw the latter from the guiding element 31 for inspection or replacement.

The arrangement shown in Fig. 5 differs from that illustrated in Figs. 3 and 4 in that the lever 33 which is quite similar to the lever 25 of Figs. 3 and 4 is so located with respect to the brush 5 that it exerts on said brush a pressure having two components. One of these components yieldingly forces said brush into contact with the commutator face while the other opposes the action of the centrifugal force on the brush 5. To enable the lever 33 to perform this dual function a part of the brush 5 is cut away so as to present a suitably inclined surface to the end of the lever 33. In Fig. 5 the sides of the guiding member 31 are shaped to suit the modified position of the pin 22 with respect to the brush 5.

In the embodiment shown in Figs. 6 and 7 the member 23 is shaped to guide the brush 5 into operative relation with the working face of the commutator 6 of L-shaped cross section. The side members of the guide 23 are hook-shaped and engage with the pin 22 held in the bracket 9. These hooks limit the travel of the guide 23 in a radial direction. This guide is held approximately in its normal position by the flat spring 27. One end of this spring is attached to the bracket 9 at 36; the other end is provided with extensions 28 which cooperate with shoulders of the guide 23 to prevent the hooks of the guide 23 from slipping off the pin 22. The brush 5 located within the upper end of the guide 23 is held in yielding contact with the operating surface of the commutator by the lever 25 loosely mounted on the pin 22 and under the control of the spring 26. The travel of the brush in a radial direction is limited inwardly by a part of the spring 27 and outwardly by well rounded conical knob 24 attached to the guide 23 and cooperating with a suitable groove in the brush 5.

When the brush gear revolves the action of the centrifugal force on the guide 23 tends to bring the hooks of the guide into cooperation with the pin 22 and the action of the centrifugal force on the brush 5 tends to the same end by causing the brush to exert a pressure on the conical projection 24.

Again assuming that the revolving member has a certain amount of end play, and that the brush 5 must, therefore, move axially with

respect to the brush gear and the revolving member in order to retain its operative or surface contact with the working face of the commutator, let it be assumed that normally the conditions are as exaggeratedly depicted in Fig. 8. Let the original points of contact between the brush 5 and the centrifugal force opposing means 24 be M and N and let the original points of contact between the pin 22 and the hooks of the guiding member 23 be M' and N'. If the revolving member now moves from left to right so as to bring the pin 22 into that position with relation to the working face of the commutator 6 which is shown in Fig. 9, the brush 5 will move inwardly to some extent, will retain its surface contact with the commutator 6 and the conical member 24 will be displaced on the brush 5 bringing about a displacement between the original points of contact M and N as well as a displacement between the original points of contact M' and N' as shown in Fig. 9. But, whereas the revolving member of the dynamoelectric machine, and with it the pin 22, has moved relatively to the commutator face through the distance $a+b$ the codirectional displacement between the original points of contact M and N amounts to about one tenth of that distance while that between the original points of contact M' and N' amounts to even less. Obviously, the same relative displacement would occur if the face of the commutator were correspondingly displaced with respect to the bracket 9. While the revolving member moves in the manner described in connection with Figs. 8 and 9, the original points of contact between the hub of the lever 25 and the pin 22 obviously undergo displacements quite similar to those between the points M' and N'. In this manner the work of friction between parts of the brush gear and between the brush and the brush gear, caused by the said axial displacements, is greatly reduced and sluggishness of brush is avoided without it being necessary to subject the brush to such axial pressure as would involve undue friction losses between the brush and the commutator. In order to remove brush 5 of Figs. 6 and 7 for inspection or replacement, it is necessary to pull the lever 25 away from the brush and slightly depress the spring 27 by means of its wings 28. Depression of the spring 27 also permits of the removal of the guide 23 by unhooking same from the pin 22.

It will be clear that various changes may be made in this disclosure without departing from the spirit of this invention, and it is, therefore, to be understood that this invention is not to be limited to the specific details here shown and described.

What I claim is:

1. In a dynamoelectric machine having a stationary and a revolving member, a commutator on one member having a working

face substantially at right angles to the axis of the machine, a brush carried by the other member and free to move with respect to said other member substantially parallel to the axis of the machine, means for producing relative rotation between the brush and the commutator, means for yieldingly pressing said brush into axial and surface contact with the working face of the commutator, and means for opposing a radial movement of the brush, said last named means being so constituted that in case of relative axial displacement between the brush and said other member the axial displacement between original points of contact between brush and the most effective parts of the radial movement opposing means is less than the relative axial displacement between the brush and the other member.

2. A commutator having a working face, a revolving brush cooperating with the commutator and free to move relatively to its support along a line normal to the working face of the commutator while retaining a surface contact with said face, and mechanism for opposing the effect of centrifugal force on the brush along a line at an angle to the normal to the working face of the commutator characterized by the fact that in case of relative motion between the brush and its support in a direction normal to the commutator face the codirectional displacement between original points of contact between parts of said mechanism is less than the concurrent displacement between the brush and its support.

3. In a dynamoelectric machine having a stationary and a revolving member, a commutator on one member having a working face substantially at right angles to the axis of the machine, a revolving brush carried by the other member, said brush cooperating with the commutator and free to move relatively to its support along a line normal to the working face of the commutator while retaining a surface contact with said face, means for limiting the radial displacement of the brush characterized by the fact that in case of relative motion between the brush and its support in a direction normal to the commutator face the codirectional displacement between the brush and said limiting means is less than the concurrent displacement between the brush and its support.

4. A commutator having a working face, a revolving brush free to move relatively to its support along a line normal to the commutator face while retaining a surface contact with said face, means for guiding the brush into operative relation with the commutator face, means for yieldingly pressing said brush into contact with the commutator face, and mechanism associated with the guiding means characterized by the fact that in case of relative motion between the brush

and its support in a direction normal to the commutator face the codirectional displacement between original points of contact between parts of said mechanism is less than 5 the concurrent displacement between the brush and its support.

5. In a dynamoelectric machine, a commutator having a working face substantially at right angles to the axis of the machine, 10 a revolving brush gear support, a brush, means loosely pivoted on said support for revolving the brush and guiding it into operative relation with the commutator face, said brush being free to move relatively to the 15 support substantially parallel to the axis of the machine, and means for opposing a radial movement of the brush said last named means being so constituted that in case of relative axial motion between the brush and 20 the support the codirectional displacement between original points of contact between brush and the most effective parts of the radial movement opposing means is less than the axial displacement between the brush and 25 said support.

6. In a dynamoelectric machine, a stationary commutator having a working face substantially at right angles to the axis of the machine, a revolving brush gear support comprising a pin, a brush, means loosely hinged on the pin for guiding the brush into operative relation to the commutator face and 30 pressed against said pin by centrifugal force, means for yieldingly pressing the brush into 35 operative contact with the commutator face, and retaining means providing a contact sur-

face between the brush and the guiding means adapted to take the centrifugal thrust of the brush on the guiding means, said surface being so formed and controlled that in 40 case of relative axial motion between the brush and the support the codirectional displacement between original points of contact between the brush and said surface is less than the axial displacement between the brush 45 and the support.

7. In a dynamoelectric machine, a stationary commutator having a working face substantially at right angles to the axis of the machine, a brush, a revolving brush gear 50 adapted to guide the brush into operative relation to the commutator face, and means for yieldingly pressing the brush into operative contact with the commutator and for counteracting the action of the centrifugal 55 force on the brush.

8. In a dynamoelectric machine, a stationary commutator having a working face substantially at right angles to the axis of the machine, a brush, a pin attached to the brush 60 and approximately parallel to the working face of the commutator, a revolving brush gear support, means loosely pivoted on the support and loosely hinged about the brush pin for yieldingly pressing the brush into 65 operative contact with the commutator face and for counteracting the effect of the centrifugal force on the brush.

In testimony whereof I affix my signature this 6th day of May, 1927.

JAROSLAW K. KOSTKO.
